END CONNECTOR FOR WATCH BRACELETS

Otto Robert Kostka, Providence, R. I., assignor
to Marvel Jewelry Mfg. Company, Providence,
R. I., a corporation of Rhode Island

Application March 29, 1949, Serial No. 84,039

9 Claims. (Cl. 24—241)

1

The present invention relates to improvements in an end connector for watch bracelets and has for an object the provision of an improved end connector for use in connection with wrist bands and bracelets for watches which permits of the band or bracelet being quickly and easily attached to and detached from a wrist watch.

Another object of the present invention is to provide an improved end connector which establishes a strong and dependable connection between the watch and the bracelet so that the likelihood of accidentally becoming unfastened is negligible.

A further object of the present invention is to provide an improved device of this type which when closed and in use on the wrist of the wearer will present a compact, neat and highly ornamental appearance with the operating mechanism completely concealed.

A still further object of the present invention is to provide an improved structure which comprises relatively few parts of simple construction so that the cost of manufacture is small and the chance of becoming broken or out of order is slight. Accordingly, it is not necessary for repairing jewelers to have on hand a large variety of replacement parts and the owner of a bracelet provided with the improved device thereon is not subjected to the annoyance caused by frequent breakage of parts.

With the foregoing and other objects in view, the invention will be hereinafter more fully described and more particularly pointed out in the appended claims.

In the drawings, in which the same parts are denoted by the same reference numerals throughout the several views,

Figure 1 is a top perspective view of the improved device constructed in accordance with the present invention and illustrated in the closed condition as applied to a wrist watch and an expandable bracelet.

Figure 2 is an enlarged bottom perspective view of the improved end connector with the device open and parts broken away.

Figure 3 is a sectional view taken on the line 3—3 of Figure 2.

Figure 3A is a fragmentary view showing the initial engagement of the latch member with the keeper during the movement of the latch member to its latching position.

Figure 4 is a top perspective view of the bottom plate.

Figure 5 is an exploded perspective view of the top plate and the latching means,

2

Figure 6 is a sectional view taken on the line 6—6 of Figure 3, and

Figure 7 is a fragmentary view of the keeper and the latch member showing in dotted lines the initial engagement of the latch member with the keeper and in full lines the fully latched position of the latch member and the keeper.

Referring more particularly to the drawings, 10 indicates a conventional wrist watch having a usual knuckle 11, and 12 indicates an expandable bracelet of the conventional type which is adapted to be detachably connected to the knuckle 11 of the wrist watch 10.

The bracelet 12 is removably attached to the wrist watch 10 by the improved end connector which comprises a top plate 13, a bottom plate 14, a spring 15 and a movable U-shaped latch member having legs 16 and 16^a and a connecting portion 16^b.

The top plate 13 has a medially disposed V-shaped depression or cradle 17 and rearwardly of the depression 17 the top plate has an area 18 which is provided with a substantially flat inner and outer surface. Forward of the depression 17 the top plate has areas 19 and 20, the inner surfaces of which are substantially flat. The top plate 13 has at one side thereof downwardly extending flanges 21 and 22 which are angularly disposed to one another and the flange 21 has a V-shaped portion 23 which conforms to the contour of the V-shaped recess 17.

A depending flange 24 is disposed at the forward edge of the flat area 19 of the top plate and a similar flange 25 is disposed at the forward edge of the area 20 of the top plate.

The portion of the top plate between the areas 19 and 20 is cut-away as at 26 to provide a recess for the reception of the knuckle 11 of the wrist watch 10. At the rear of this cut-away portion 26 the top plate is bent downwardly to provide flanges 27, 28 and 29.

The flange 28 is disposed forwardly of and parallel to the longitudinal axis of the depression 17 of the top plate and the flanges 27 and 29 are disposed at substantially right angles to the flange 28. The flange 27 is substantially the same depth as the flange 28 and its rear edge is joined to the flange 28. The forward edge of the flange 27 is inclined downwardly and rearwardly as indicated at 30 to provide a cam surface on the flange 27. The flange 29 has a depth less than that of the flange 28 and has its rear edge joined thereto and its forward edge is secured to the inner face of the flange 25.

The top plate 13 has at its opposite side depending flanges 31 and 32 which are angularly

disposed at its opposite side depending flanges 31 and 32 which are angularly

disposed to one another. The forward edge of the flange 31 is united to the flange 25 and the flange 32 has an angularly disposed portion 33. The rear edge portion of the top plate is bent downwardly to provide flanges 34 and 35 which are of lesser depth than the flanges 21 and 33 and are connected thereto, respectively. The flanges 34 and 35 are disposed at an angle of the order of 90 degrees to one another and are joined together by a semi-circular portion 36.

The spring 15 is disposed within the top plate in an upstanding position and has the medial portion of its upper edge curved as indicated at 37 to be received by the depression or cradle 17. The upper edge of the spring 15 forwardly and rearwardly of its medial portion 37 is substantially flat as indicated at 38 and 39, respectively, and its flat portions engage the flat areas 19 and 18, respectively, of the top plate 13. The spring 15 has its medial portion longitudinally bowed outwardly as indicated at 40 and the lower edge part of the medial portion of the spring is cut-away to provide a keeper 41 at the forward edge of the spring and a depending lug 42 adjacent the rear edge of the spring.

The bottom plate 14 is substantially flat and its outer contour corresponds generally with that of the top plate 13. The plate 14 has angularly disposed side edges 43 and 44 engaging the inner faces of the flanges 22 and 21, respectively, of the top plate and the edge 44 of the bottom plate 14 has a notch 45 which receives the lug 42 of the spring 15. The rear edge portion of the bottom plate 14 underlies the flanges 34 and 35 of the top plate and the bottom plate 14 has its rear edge 46 engaging the inner face of the flange 33 of the top plate 13.

The bottom plate 14 is also provided with angularly disposed side edges 47 and 48 engaging the inner faces of the flanges 31 and 32, respectively, of the top plate 13 and forward edges 49 and 50 which engage the inner faces of the flanges 25 and 24, respectively, of the top plate. The bottom plate 14 has adjacent its side edge 47 an upwardly turned flange 51 which engages the flat surface 20 of the top plate 13. Adjacent its edge 43 the bottom plate 14 is cut-away as at 52 so that the keeper 41 will be exposed in order to permit the nose 53 of the leg 16^a of the latch member to engage it.

The other leg 16 of the latch member is pivotally mounted in a U-shaped bearing having legs 54 and 55 and a connecting portion 56. The legs 54 and 55 have downwardly extending lugs 57 which are received by openings 58 in the bottom plate 14. At each side of the lugs 57 the legs 54 and 55 are provided with shoulders 59 which engage the inner surface of the bottom plate 14 when the lugs 57 are received by the openings 58. The lugs 57 may be upset as by peening to secure the bearing to the bottom plate 14.

The improved connector is secured to the end link 60 of the under portion of the bracelet 12 by a rivet 61 which extends through an opening 62 in the bottom plate 14. The rivet 61 is received by the pocket formed by the flanges 34 and 35 and the semi-circular portion 36 of the top plate 13. The end link 63 of the upper portion of the bracelet 12 is received by a recess 64 formed by the flanges 34 and 35 of the top plate 13. The link 63 rests upon the upper surface of the rear edge portion of the bottom plate 14. The bottom plate 14 is retained within the top plate 13 by the bent over flanges 65 which engage the lower surface of the bottom plate. The for-

mation of the flange 51 on the bottom plate provides a recess 66 which accommodates the connecting portion 16^b of the movable latch member when the latch member is in its closed position.

In the use of the device when it is desired to attach the wrist watch 10 to the bracelet 12, the leg 16^a of the movable latch member is threaded through the opening in the knuckle 11 of the wrist watch and the knuckle 11 is moved into the recess 26. During this operation the nose 53 of the movable latch member engages the keeper 41 of the spring 15 and moves it to the dotted line position shown in Figure 3 of the drawing. As shown particularly in Figures 3A and 7 of the drawings, the keeper 41 is inclined upwardly and outwardly to facilitate the initial engagement of the nose 53 with the inner face of the keeper.

Since the lug 42 of the spring is in contact with the sides of the notch 45 of the bottom plate, the rear end portion of the spring will be restrained against any appreciable movement and the forward portion of the spring will pivot on the bowed portion 40 of the spring. This pivotal movement of the forward portion of the spring will place the spring under tension and permit the nose 53 of the movable latch member to move past the keeper 41. As soon as the nose 53 has cleared the keeper 41 the spring will immediately move from the dotted line position shown in Figure 3 to the full line position shown in that figure and the nose 53 will be received by the notch 67 formed by cutting away the upper forward edge portion of the keeper 41. The keeper 41 will retain the leg 16^a of the movable latch member in its closed position so that the connector will be securely attached to the wrist watch.

In order to remove the wrist watch from the bracelet it is merely necessary to press against the keeper 41 to move the same out of the path of the nose 53 of the movable latch member and to swing the movable latch member on its bearing 56 to the open position shown in Figure 2. The inclined forward edge 30 of the flange 21 will act as a cam on the leg 16^a to move the leg 16 into engagement with the inner surface of the leg 54 of the U-shaped bearing member so that in its closed position the movable latch member will be restrained against movement in a forward or rearward direction. The inclined edge 30 of the flange 21 will also act as a stop for limiting the movement of the keeper 41 towards the recess 26 so that in moving the leg 16^a to its closed position the nose 53 will be able to cam the keeper 41 to the dotted line position shown in Figure 3. Since the edge 30 of the flange 21 is inclined upwardly and forwardly the edge 30 will engage the spring 15 so as to limit the movement of the keeper 41 into the recess 26, so that when the leg 16^a is moved to its closed position the nose 53 will not jam on the keeper, but will cam the keeper 41 to the dotted line position shown in Fig. 3.

What I claim is:

1. For use in joining a watch casement having open ended attaching knuckles to a bracelet, an improved end connector for watch bracelets comprising a bottom plate having a recess therein, a top plate having downwardly depending flanges for supporting said top plate above said bottom plate, said top plate having a recess complementary to and disposed in vertical alignment with the recess in said bottom plate, a latch member hingedly carried by said bottom plate and positioned to move towards said plates at substan-

tially right angles to the planes thereof and to pass through and beyond said bottom plate recess to be received by said top plate recess, and spring means carried between said top and bottom plates positioned to engage said latch member when said latch member is swung to a seated position within said top plate recess and in a plane substantially parallel to said bottom plate, said recesses being adapted to envelope the open end portions of the attaching knuckle of the watch casement and said latch member being positioned to pass through said attaching knuckle and retain said knuckle within said recesses.

2. For use with a device having an attaching knuckle projecting therefrom an improved connector comprising a bottom plate having a recess therein, a top plate having a recess therein complementary to the recess in said bottom plate, downwardly depending flanges carried by said top plate for supporting the same vertically above said bottom plate, a bearing on one of said plates, a U-shaped movable latch member having one leg pivotally carried by said bearing and the other leg disposed to swing across the recesses in said top and bottom plates, a spring disposed between said plates and having a keeper portion disposed in the path of movement of said other leg of the latch member, and a nose on said other leg of said latch member positioned to engage and move said keeper portion out of the path of movement of said other leg of said latch member thereby placing said spring under tension until said nose clears said keeper portion and sets therebehind to retain said other leg of the latch member in the latched position.

3. An end connector for watch bracelets as claimed in claim 1 characterized by the fact that said top plate has a cradle and that said spring has a curved portion received by said cradle.

4. An end connector for watch bracelets as claimed in claim 3 characterized by the fact that said spring has a lug and that said bottom plate has a notch for receiving said lug.

5. For use with a device having an attaching knuckle projecting therefrom an improved connector comprising a bottom plate having a recess therein, a top plate having a recess therein complementary to the recess in said bottom plate, means for securing said plates together in spaced apart relation, a latch member having a portion pivotally mounted on one of said plates and having a second portion disposed to move towards said plates at substantially right angles to the planes thereof and to swing across said recesses, and a spring between said plates and having a portion in the path of movement of said second portion of the latch member and adapted to be moved by said second portion of the latch member out of the path of movement thereof, thereby placing said spring under tension until said second portion of the latch member clears said spring portion and sits therebehind to retain said second portion of the latch member in latched position.

6. An end connector for watch bracelets as

claimed in claim 5 characterized by the fact that the top plate has a cam surface for engaging said other leg of the movable latch member to bind the pivoted leg of the latch member against its bearing to prevent forward and rearward movement of the movable latch member when in its closed position.

7. An end connector for watch bracelets as claimed in claim 6 characterized by the fact that said top plate has a cradle and flat portions forwardly and rearwardly of the cradle, that said spring has an intermediate curved portion received by the cradle, that said spring has flat portions at each side of its curved portion for engagement with the flat surfaces of the top plate.

8. An end connector for watch bracelets as claimed in claim 7 characterized by the fact that said top plate and bottom plate have cooperating flanges and edges respectively to retain the bottom plate in its proper position in the top plate.

9. For use in joining a watch casement having open ended attaching knuckles to a bracelet, an improved end connector for watch bracelets comprising a bottom plate having a recess therein, a top plate having downwardly depending flanges for supporting said top plate above said bottom plate, said top plate having a recess complementary to and disposed in vertical alignment with the recess in said bottom plate, a latch member hingedly carried by said bottom plate and positioned to pass through and beyond said bottom plate recess to be received by said top plate recess, and spring means supported and held in operative position by both said plates and having a keeper normally positioned within said top plate recess to engage said latch member when said latch member is swung to a seated position within said top plate recess and spaced from and in a plane substantially parallel to said bottom plate, said recesses being adapted to envelope the open end portions of the attaching knuckle of the watch casement and said latch member being positioned to pass through said attaching knuckle and retain said knuckle within said recesses.
